(57) **CLAIM**

The ornamental design of a system storage unit front bezel, as shown and described.

DESCRIPTION

FIG. 1 is a front, right perspective view of the system storage unit front bezel;

FIG. 2 is a front, left perspective view of the system storage unit front bezel;

FIG. 3 is a front view of the system storage unit front bezel;

FIG. 4 is a top view of the system storage unit front bezel;

FIG. 5 is a right side view of the system storage unit front bezel; and

FIG. 6 is a left side view of the system storage unit front bezel.

The bottom view of the system storage unit front bezel is identical to FIG. 4.

The back view of the system storage unit front bezel is unornamented.

The broken lines are shown in the views for illustrative purposes only and form no part of the claimed design
